UNITED STATES PATENT OFFICE.

CHARLES S. BUSHNELL, OF ROCHESTER, NEW YORK, ASSIGNOR TO GENERAL RAILWAY SIGNAL COMPANY, OF ROCHESTER, NEW YORK.

INTERMITTENT INDUCTIVE TRAIN-CONTROL RECEIVER.

Application filed October 11, 1926. Serial No. 140,891.

The invention relates to automatic train control and has more particular reference to a receiving means for a train control system of the intermittent inductive type.

- 5 In one type of intermittent train control, influences corresponding to traffic conditions are transmitted to a moving vehicle at spaced points along the trackway by means of the change in flux in the magnetic circuit of a receiver carried on the vehicle, when such circuit is brought into close proximity to a magnetic body located on the trackway. The influences thus received are transmitted to the vehicle control apparatus by means 15 of voltages induced in a suitable coil or coils linked by the magnetic circuit of the receiver, a flux in the circuit being supplied by the same or another coil or coils energized from a suitable car-carried source.
- 20 The receiver must generally be so located on the vehicle as to be close to the road bed so that the air gap through which the flux must pass, may be of minimum length. It is also desirable that loss due to eddy currents in 25 the magnetic structure and in the receiver housing be reduced to a minimum, that the receiver be securely mounted so that the variations in position of the same during operation may be a minimum, that the coils and 30 core construction be very rugged to withstand the very considerable vibrations and shocks to which it is subjected, and that the electrical connections be suitably protected.
- With the above and other considerations in 35 mind it is proposed in accordance with this invention to provide an intermittent inductive receiver which will satisfy the above set forth requirements in a more satisfactory manner than has heretofore been realized.
- 40 Further objects of the invention are, to simplify the construction, decrease the cost of manufacture, and increase the efficiency and length of life, of devices of this character.

- 45 Further objects, purposes, and characteristic features of the present invention will appear as the description progresses, reference being had to the accompanying drawings, given solely by way of example, and showing 50 one form of device embodying the present invention. In the drawing:

Fig. 1 is a side elevation of a receiver constructed in accordance with this invention, with parts broken away to more clearly show 55 the structure.

Fig. 2 is a sectional elevation on line 2—2 of Fig. 1, viewed in the direction of the arrows.

Fig. 3 is a sectional plan on line 3—3 of Fig. 1, viewed in the direction of the arrows. 60

Fig. 4 is a sectional elevation on line 4—4 of Fig. 1, viewed in the direction of the arrows.

Fig. 5 is a plan view of the core and coil structure removed from its casing. 65

Fig. 6 is a bottom plan view of the receiver, with parts omitted for clearness.

Fig. 7 is an end elevation of the receiver connected in place, with the adjacent car structure shown in dot and dash lines. 70

Fig. 8 is a side elevation of the receiver fastened in place, with the adjacent car structure and track rail shown in dot and dash lines.

Briefly stated, the receiver shown and described for exemplifying this invention, comprises a generally rectangular casing C, having two spaced upstanding arms A, for permitting adjustable attachment of the receiver to a railway vehicle, and a core structure, 80 carrying a primary coil P and a secondary coil S, housed in the casing.

Going more into detail, and referring to the drawings, the casing C, with its arms A, is preferably cast or otherwise formed, in 85 one piece, of suitable non-magnetic material such as phosphor bronze or the like, and formed with two end openings closed by end plates 1 fixed to the casing by bolts 2, an elongated narrow side opening closed by a 90 side plate 3 fastened in place by screws 4, and a bottom opening, closed in a manner to be later described. The casing is also supplied with end inlets 5 and 6, for lead-in wires, one inlet generally being used for all 95 the wires, dependent upon the location of the casing on the vehicle, the one not in use being closed by a plug 7.

The coil and core structure housed in the casing includes two coils, a primary coil P 100 and a secondary coil S, alike structurally, but having different electrical characteristics as regards resistance and a different number of turns, and a core for the coils.

Each coil P and S, is wound directly on, 105 and is insulated from, a straight laminated core 8, of silicon steel or like magnetic material, and is held onto the core, at the ends, by annular insulating discs 9 mounted on the core. The upper disc 9 is held in place by 110

means of clamps 10, bolted on opposite sides of the squared upper core end 11, by bolts 12 passing through such end of the core. The lower disc 9 is held in place on the core by a pole shoe 13 first screw connected to the core end, and then welded to the core. Each pole shoe 13 is slotted as at 14, to cut down circulation of eddy currents as far as possible, and thus prevent iron losses.

10 Each coil P and S with its corresponding coil, is passed up into the casing through the bottom opening, into enlarged cylindrical casing ends 15, and held therein by bolts 16 connecting the pole shoe to flanges 17 on the casing and surrounding the bottom opening. A set screw 19 having a lock nut passes through the top of the casing and bears against a washer 20, having a centering finger 21 received in a socket in the upper end of the core. The screw 19 acts to hold the core and its coil firmly in place in the casing, the washer 20 operating to distribute the pressure of the screw over the core lamineæ to prevent distortion of the same.

25 A back strap 22, as best shown in Fig. 5, built up of lamineæ, and of a general U shape, is passed through the casing side opening, with the ends of its legs 22¹ abutting squarely against the squared upper ends of the coil cores. The coil core in each case is firmly clamped to the back strap and an inwardly projecting boss 23 formed on the casing, by a T-head bolt 24 passing through the rear of the casing, the upper end of the coil core, and a leg of the back strap, with a clamping nut and washer 25 on its front threaded end. A portion of the lamineæ of the back strap is cut away around the hole for the bolt 24 to accommodate a bearing plate 26 for distributing the pressure of the bolt 24, over the lamineæ of the back strap. The back strap is further held in position within the casing, by two through bolts 27.

On referring to Figs. 4 and 6 in particular, it will be noted that the pole shoes are positioned unsymmetrically relative to the coil cores, and cover only a portion of the width of the bottom opening in the casing. A plate 28, of brass or other non-magnetic material, is bolted to the casing by bolts 29, to cover the remaining width of the bottom opening of the casing. By this arrangement of parts, the centers of the pole shoes 13 are positioned outwardly of the center line of the coils and casing proper, to thus position the pole shoes the proper distance away from the vehicle to which the receiver is to be fastened, while at the same time permitting the center of gravity of the entire receiver to fall inwardly of the center lines of the pole shoes, thereby to increase the stability of the support of the receiver on the vehicle.

65 A plate 30 of insulating material is bolted to the flanges around the bottom opening of

the casing, to close the rest of the opening and prevent entrance of foreign matter.

The side plate 3 is connected to the back strap 22 by means of screws 31, the plate 3 having two circular openings 32 to accommodate the nuts 25 on the T head bolt.

Care is taken, in fastening the coils, core, back strap, and pole shoes to the casing, to thoroughly insulate them from the casing, at all points of contact, by means of insulating washers and gaskets, and insulating bushing for the bolts, all as shown on the drawings. Further, suitable packing gaskets are provided for the various cover plates connected to the casing, and the connecting bolts, as shown, are generally supplied with spring lock washers or the like. A terminal board 33 is fastened to integral lugs 34 on the casing, and the four terminal wires, two for each coil, are connected to four lead in wires 35, by clamping them on terminal posts 36 on the board 33. A cover block 37 is fastened over the board 33 by screws 38. The wires for the coils can be brought out of the casing through either end, or both ends according as convenience dictates.

The construction described above operates to rigidly interconnect the coils, core, and casing, so as to prevent any relative movement therebetween due to jars and vibration, and prevents, in a simple and effective manner, shifting of the coils on the core, as is more liable of occurrence when the coils are wound on spools, and the spools slipped onto the core.

For aiding in adjustably and securely fastening the receiver to a vehicle, the arms A are furnished with positioning screws 39, carried in integral lugs 40 at the upper ends of the arms, and extend parallel to elongated vertical slots 41 in the arms. The arms A each have a saw toothed rear surface 42 interlocking the connecting members or washboards 44 fitted by means of arms 45, over sideways extending lugs 46 cast integral with the journal box. The lugs 46 have slots 47 receiving connecting bolts 48 with their heads 49, held back of the lugs. The connecting bolts extend through the lugs 46, the washboards, and slots 41 in the arms A, and carry square washers 50 bearing against machined surfaces surrounding the slots 41, and held onto the bolts 48 by castellated nuts 51.

In attaching the receiver to a vehicle, the slots of arms A are passed over the connecting bolts 48, and the washers and nuts 50, 51 are placed on such bolts, and the positioning bolts 39 are adjusted to give the proper elevation of the pole shoes 13 above the track rail 52 when their ends are against the square washers 50. The bolts 39 are backed off from the square washers, before final tightening of the nuts 51, and then nuts 51 are tightened,

drawing the cooperating toothed parts 42 and 44 together to firmly clamp the receiver in place. Then the positioning bolts 39, which are not intended to carry any of the weight of the receiver while in operation, are screwed down to lightly bear against the square washers 50, and are then locked in place. If necessary to remove the receiver from the vehicle, the locked positioning bolts 39 permit ready re-attaching of the receiver in its previous adjusted position. This attaching means permits ready adjustment of the receiver in a vertical direction to compensate for wear on the rails 52, and the car wheels 53.

15 The above specific description of one form of device embodying the present invention has been given solely by way of illustration, and is not intended, in any manner whatsoever, in a limiting sense. Obviously, this invention 20 can assume many different physical forms, and is susceptible of numerous modifications, and all such forms and modifications are desired to be included by this invention, as come within the scope of the appended claims.

25 Having described my invention, I now claim:—

1. In a receiver, a casing, means for fastening the casing to a vehicle, a core in the casing, coils on the core, and pole shoes fixed to the 30 core and each positioned with its center line to that side of the core center line which is remote from the vehicle.

2. In a receiver, a casing, means to fasten the casing to a vehicle, a core and coils housed 35 in the casing, and pole shoes on the core offset from the center line of the core and away from the vehicle side of the casing, so as to position the pole shoes outwardly of the casing.

40 3. In a receiver, a casing, core and coil structure in the casing, spaced projecting arms on the casing, and means for adjustably fastening the arms on opposite sides of a car truck journal box.

45 4. In a receiver, a casing, core and coil structure in the casing, spaced projecting arms on the casing, in combination with a car truck journal box, a lug projecting to each side of the journal box, and means for adjustably fastening the arms to the lugs.

50 5. In a receiver, a casing, core and coil structure in the casing, spaced projecting arms on the casing, a car truck journal box, lugs on the sides of the box, slots in the casing 55 arms, bolts carried by the lugs and passing through the slots, and nuts on the bolts for adjustably clamping the casing arms to the journal box lugs.

6. In combination, a receiver for train control, spaced arms on the receiver, a car truck 60 journal box straddled vertically by the said arms, and means for adjustably connecting the arms to the journal box.

7. A car truck journal box, a lug on each side of the box, a casing, core and coil structure in the casing, spaced arms on the casing straddling the journal box, bolts passing through the lugs, and the slots in the arms, to adjustably fasten the casing to the journal box, a bearing block on each bolt, and a 70 threaded spacing rod in each arm resting at one end on the bearing block.

8. In a receiver, a casing, a core structure in the casing comprising two spaced cores, and a separate back strap connecting the 75 spaced cores, and an insulated coil wound directly on, and non-removable from, each of the spaced cores.

9. In a receiver, a casing, two core and coil units in the casing, a back strap bolted 80 to, and interconnecting, the cores of said two units, each said unit including a core, a coil wound directly on the core, and insulating discs on the core at the ends of the coil and held in place at one end by a pole shoe fixed 85 to the core, and at the outer end by clamps bolted to the core.

10. In a receiver for automatic train control, a core, a coil wound directly on the core, and insulating discs on the core at the 90 ends of the coil and held in place at one end by a pole shoe fixed to the core, and at the outer end by clamps bolted to the core.

11. In a receiver, a casing, two core and coil units in the casing each comprising, a 95 core, a coil wound directly on the core, a separate back strap in the casing, and bolts each passing through a casing wall, a core of one of the units, and the back strap, for tightly clamping the units, the back strap, and the 100 casing, in fixed relation.

12. In a receiver, a casing, core and coil structure in said casing, projecting arms integral with said casing and spaced to straddle a car truck journal box, and means for fastening said arms at the opposite vertical sides of such journal box.

13. In a receiver, a casing, core and coil structure in said casing, projecting arms integral with said casing and spaced to straddle 110 a car truck journal box, and means for adjustably and rigidly fastening said arms at the opposite vertical sides of such journal box.

In testimony whereof I affix my signature.

CHARLES S. BUSHNELL.
